UNITED STATES PATENT OFFICE

HUGH W. SANFORD AND WILLIAM O. MCKAMEY, OF KNOXVILLE, TENNESSEE

MINE CAR

Application filed January 26, 1931. Serial No. 511,412.

Our invention relates particularly to mine cars and other cars of a type used for carrying loose material.

For a car of this type, reference is made to Letters Patent of the United States, No. 1,486,547, granted to Hugh W. Sanford, March 11, 1924.

Our improvement is applicable to the end structures of mine and similar cars, cars, the end structures comprising bumpers or buffers and coupling means. This application relates particularly to end structures comprising bumpers or buffers and three inter-related coupling links, the bumpers or buffers being formed relative to use of those links.

The object of the invention is to adapt the bumpers to make room for the middle link when adjacent cars are moved relatively toward each other to make the opposing bumpers to bear upon each other.

In the accompanying drawings,

Fig. 1 is a plan of a structure embodying our improvement;

Fig. 2 is an elevation looking at the structure of Fig. 1 toward the upper end of the sheet;

Fig. 3 is an elevation looking at the right hand end structure of Figs. 1 and 2 from the left, the links being omitted;

Fig. 4 is a perspective of the metal bumper member forming a part of the end structure of the car;

Fig. 4a is a plan of a part of a wood filler;

Fig. 5 is a section on the line 5—5 of Fig. 4;

Fig. 6 is an upright section on the line 6—6, of Fig. 1, looking toward the left.

Referring to the drawings, A, A are side sills. In the form shown by the drawings, these sills are of channel-shape each having an upper flange, A1, and a lower flange, A2, both flanges being directed outward.

B is the steel plate member of the end sill structures. This has the upright web, B1, and an upper horizontal flange, B2, and a lower horizontal flange, B3. The corners of the flange, B2, are cut to make slanting edges, B4, and the corners of the lower flange, B3, are similarly cut to make slanting edges, B4. (Fig. 1).

With this member, B, are combined other

members to form the complete end sill structure in a general way as described in said Patent, No. 1,486,547, but with material differences, as will appear further on herein.

In the form shown in the drawings, the plate member, B, is long enough to partially over-lap the adjacent ends of the side sills, A. Said plate member and the side sills are joined to each other by means of corner angle members, C, which are unitary castings such as are described in said Patent, No. 1,486,547. One arm or blade, C1, of each angle member rests against the outer flat face of the upright web of the adjacent side sill, A, and is secured to said web by rivets, A3, extending through said arms and said web. The drawings show six such rivets. The other arm or blade, C2, of each angle member lies against the adjacent part of the back face of the upright web, B1, of the plate member, B. Rivets, C3, extend through said arm and said web to join said parts to each other. In the drawings, six such rivets are shown.

Each end sill structure is a duplicate, in reverse, of the other, it being understood that such a structure is placed on each end of each car, so that when two cars are coupled to each other, a pair of such end structures will be opposite each other and may meet when either car is moved toward the other.

Referring to either end structure, an inner or second member, D, of strong wood, preferably oak, is placed on the lower flange, B3, and against the upright web, B1, of the plate member, B. The upper and the lower and the inner faces of this wood member, D, are straight; while the outer face of the wood member conforms approximately to the outer edges of the flanges, B2 and B3, of the plate member, B, excepting that from the outer ends toward the middle, the wood member, D, is gradually extended outward away from the edges of said flanges, until near the middle of the member, B, where at D1, the upper part of its upright face is indented, the width of the indentation being somewhat more than the thickness of the upright middle link, F9. This wood member constitutes a filling or cushion member. It rests on the lower flange, B3, of the plate member, B. Its height is less than the

height of the upright web, B1, of the plate member, B. Thus space is left between the wood member, D, and the upper flange, B2, of the plate member, that space being sufficient 5 to receive one of the end coupling links, F10.

10 A metal bumper member, E, is placed on the filling or cushion member, D, at the middle of the latter. The member, E, is curved and channel-form, having an upright web, E1, and an upper flange, E2, and a lower flange, E3. The upright web, E1, and the upper flange, E2, have an indentation, E4, at the meeting of said web and said flange, said indentation being inclined and conforming approximately to the indentation, D1, in the cushion member, D. Thus all of the web, E1, bears against the outer face of the cushion member, D. A part of the lower flange, E3, underlaps the flange, B3, of the plate member, B.

15 Four rivets or bolts, D2, are shown extending through the upper flange, B2, and the cushion member, D, and the lower flange, B3. Between the upper flange, B2, and the cushion member a spacing sleeve, D3, surrounds each bolt to maintain the distance between said flange and the cushion member.

20 A reinforcing plate, G, is placed on and riveted to the middle part of the upper flange, B2. A shaft form upright coupling pin, G1, extends loosely through the plate, G, and the upper flange, B2, and the adjacent end link, F10, and the upper flange, E2, and the cushion member, D, and the lower members, B3 and E3.

25 Each of the end links, F10, normally lies in a horizontal plane and flatwise on the adjacent flange, E2; and said links are joined by the middle link, F9, which is in an upright plane and is shown shorter than the end links, F10—preferably only long enough to couple the longer end links. The end links are made long enough, and the space between the coupling pins, G1, and the upright web, B1, of the plate member, B, is sufficient to allow each of said end links, F10, to slide endwise toward the adjacent web, B1, when the two opposing end structures are driven toward or against each other.

30 When force is applied to either car which serves to separate the cars and put the three links under tension, the long links, F10, F10, are held in the horizontal plane which is parallel to and a little above the upper faces 35 of the flanges, E2, of the bumper member, and the short middle link is suspended between the upper parts of the metal bumper member, E, and substantially out of the indentations, E4.

35 When those cars approach each other to eliminate the tension on the three links, the lower part of the short, middle, upright link, F9, will be partially surrounded by the faces in the indentations, E4, while the end links, F10, are allowed to remain in said horizontal

plane and continue to be slidable on the upper flanges, E2, of the bumper. The indentations, E4, are preferably so formed as to allow the link, F9, to seat in the indentations, resting the weight of the link, F9, on the adjacent ends of the long links, F10, being avoided.

40 If the indentations were absent, and the bumpers were driven toward each other, the middle link, F9, would be jammed by the upper parts of the bumpers or would be forced upward above the upper faces, E2, of the bumpers, whereby the adjacent ends of the long links, F10, would be carried upward, those links then being tilted out of the horizontal position.

45 As above indicated, when the bumpers meet, the end links, F10, F10, are still in the horizontal position and resting on the upper flanges, E2, of the bumpers and their sliding has not been arrested by contact with the upright webs, B1. At the same time, the middle link, F9, is seated in the indentations, E4, in such manner as to avoid exerting downward force on the adjacent ends of the links, F10, F10, and tending to tilt the links, F10, F10.

50 Here we note the function attained by extending the indentations, E4, only partially downward along the upright faces of the bumpers. If these indentations were extended further down, the above described seating and supporting of the middle link, F9, would not take place. On the contrary, the weight of the middle link would be supported on the adjacent ends of the long links. That would avoid stability of the links, F10, F10.

55 It is to be understood that the steel plate members, B, are described herein as one means for supporting the metal bumper members, E, and the coupling pins, G1. It is also to be understood that the wood member, D, is preferable, but not essential, as a member of the combination.

60 For another form of car to which our improvement is applicable, reference is made to United States Patent No. 1,562,794, granted to Hugh W. Sanford, November 24, 1925.

65 We claim as our invention:

70 1. A horizontal metal bumper for a mine or similar rail car, said bumper comprising an upright wall and said bumper also comprising an upper flange directed toward the car body and the bumper having at the middle upright longitudinal plane of the car an indentation formed by indenting the upper part of said wall and the adjacent part of said flange, the depth of the indentation being only as much as is needed to receive the lower part of one end of a horizontal coupling link resting in an upright plane, whereby the lower portion of said wall is uninterrupted.

75 2. The combination of a horizontal metal

bumper for a mine or similar rail car, said bumper comprising an upright wall and said bumper also comprising an upper flange directed toward the car body and the bumper
5 having at the middle upright longitudinal plane of the car an indentation formed by indenting the upper part of said wall and the adjacent part of said flange, the depth of the indentation being only as much as is needed
10 to receive the lower part of one end of a horizontal coupling link resting in an upright plane, whereby the lower portion of said wall is uninterrupted, and a filler member having an outer face conforming to the
15 inner upright face of the bumper member and the filler member having an upper face conforming to the lower face of the horizontal flange of the bumper and the filler member having an indentation adapted to receive the indented part of the bumper.

3. In a railway car of the kind described, a metal bumper having an upright member and a horizontal upper member directed toward the car body and said bumper having an upper indentation at the meeting of the upright member and the horizontal member and midway between the ends of said bumper, and means for supporting a coupling member adjacent said indentation whereby a part
25 of said coupling member which is below the top of said horizontal member may occupy a portion of said indentation when said bumper and a similar bumper of an adjacent car meet.

35 In testimony whereof we have signed our names, this 24th day of January, in the year one thousand nine hundred and thirty-one.

HUGH W. SANFORD.
W. O. McKAMEY.
